(57) CLAIM

The ornamental design for a modern sports coupe car body, as shown and described.

DESCRIPTION

FIG. 1 is a front perspective view of the modern sports coupe car body, showing the new design.

FIG. 2 is a rear perspective view of the modern sports coupe car body shown in FIG. 1.

FIG. 3 is a side view of the modern sports coupe car body shown in FIG. 1.

FIG. 4 is a top plan view of the modern sports coupe car body shown in FIG. 1.

FIG. 5 is a rear perspective view of the modern sports coupe car body shown in FIG. 1, with the left door opened, and the trunk opened (alternate positions).

FIG. 6 is a front view of the modern sports coupe car body shown in FIG. 1; and,

FIG. 7 is a rear view of the modern sports coupe car body shown in FIG. 1.

It will be understood that the broken lines showing tires and wheels through out the drawings are for illustrative purposes only and does not form any part of the subject design.
